UNITED STATES PATENT OFFICE

2,188,751

TOBACCO PIPE

William Wallace Hesson, Toronto, Ontario,
Canada

Application December 5, 1938, Serial No. 244,015

2 Claims. (Cl. 131—184)

My invention relates to a tobacco smoking pipe, and has for its object means arranged therewith for eliminating one of the objectionable features of all tobacco pipes, that is the plugging and clogging of the lower portion of the bowl and entrance into the stem, by the packing of the tobacco and by condensation of the moisture, which prevents a free passage through the stem.

A further object is to provide means whereby moisture is prevented from seeping and accumulating in the stem, such as nicotine, tobacco juices and saliva.

The essential features of the device embody an extension tube screw connected and screwed adjustably arranged with the mouth piece of the pipe and extending in longitudinal relation through the bore of the stem, and communicating into the lower portion of the bowl, and adapted to be adjusted and actuated to project into the bowl to dislodge any of the tobacco which may become more or less packed and clogged preventing a free draft for the smoke to be drawn from the bowl through the stem to the mouth piece.

To the above purposes my invention consists in certain novel features of construction and arrangement of parts which will be hereinafter more fully described and illustrated in the accompanying drawing, in which

Figure 1 is a sectional side elevational view of the pipe.

Figure 2 is a sectional side elevational view of the pipe showing the stem and tube adjusted for being inserted into the bowl.

Figure 3 is a sectional side elevational view of the pipe showing the stem inserted into the bowl.

Figure 4 is a perspective view of the tube removed from the stem.

Figure 5 is a perspective view of the plug, and

Figure 6 is a perspective view of a cork packing plug.

Like letters of reference refer to like parts throughout the several views of the drawing.

The pipe proper in most respects is similar to the standard tobacco pipe, embodying the bowl 10, the stem 11 and the detachable mouth piece 12.

Formed in the stem is the bore 13, somewhat larger than in the standard pipe, the bore extends to within a short distance with the bowl, from which a smaller bore 14 is formed and communicates into the lower portion of the bowl.

Fitted in the inner end of the bore 13, and engaging against a shoulder formed by the respective bores 13 and 14, is a packing plug A

preferably composed of cork or some similar material, having a central bore a formed in longitudinal relation therethrough. The essential object of the plug is to prevent moisture from entering into the bore 13.

Cemented or otherwise secured in the bore 13, intermediate the end of the stem and at a slight interval from the outer end of the packing plug A is a plug B composed of vulcanite or any suitable material, having formed therein a square bore b.

Fitted in the bore 13, and passing through the bores formed in the respective plugs B and A, is a metal tube comprising four sections and shapes—namely, a plunger portion c, a key portion d, a push coupler portion e, and an externally screw connection f.

The plunger portion c of the tube extends through the bore a, of the plug A and into the communicating bore 14, the key portion d engages in the square bore of the plug B to prevent the tube from turning when the stem is being screw adjusted on the screw connection f.

The coupler portion e of the tube is adapted to slidably action within the bore 13 and conjointly projecting into a countersink 15, in the end of the mouth piece contiguous with the internally threaded bore 16 in the mouth piece 12.

To dislodge any blockage and packing of the tobacco at the entrance of the smoke passage 30 in the tube, through which the smoke is drawn to the mouthpiece 12, the mouthpiece is turned in the direction to unscrew on the screw connection f until a slight interval separating it from the end of the shank 11 has been effected.

A forward pressure is then exerted on the mouthpiece to force the tube inwardly to cause the plunger portion c of the tube to insert into the bowl and dislodge any of the packed tobacco away from the bore opening 14.

The mouthpiece 12 may then be turned in the opposite direction to screw up on the screw connection, and by contacting with the end of the stem will draw the tube backwardly, and withdraw the plunger end of the tube from the bowl, into normal position and leave a clear and free area against the end of the tube.

The key portion d engaging in the square bore b of the plug B, secured in the bore 13, prevents the tube from turning when screwing and unscrewing the mouthpiece on the end of the tube, to force the tube inwardly or for withdrawing back to normal position.

Slight modifications may be made in the shape 55

of the tube and the means for preventing it from turning when making the actuating adjustments without deviating from the nature of my invention.

Having described my invention, what I claim is:

1. In a tobacco pipe, a tube arranged in adjustable relation with the mouthpiece thereof, said tube extending in longitudinal relation through the bore of the stem of said pipe, a plug formed with a square bore fitted and secured in the bore of the said stem, said tube passing through the said plug, a portion of the said tube being squared to register with the said bore in said plug, to prevent the tube from turning when the mouthpiece is being adjusted thereon, said tube being adapted to be actuated by the said mouthpiece in longitudinal relation to be inserted and withdrawn from the bowl of the pipe.

2. In a tobacco pipe, a tube formed and embodying a plunger portion, a key portion, a push coupler portion and a screw connection, said tube being adjustably connected with the mouthpiece of the said pipe, the said tube extending in longitudinal relation through the bore of the stem of said pipe, a plug formed with a square bore fitted and secured in the bore of said stem, the said tube extending through the said plug, and the key portion thereof registering with the said plug to prevent the tube from turning when the mouthpiece is being adjusted therewith, the plunger portion of the said tube being adapted to insert into the bowl of the pipe by an inwardly pushing on the mouthpiece, and withdrawn therefrom into normal position by screw turning the mouthpiece upon the said tube and the engagement with the end of the stem of the said pipe.

WILLIAM WALLACE HESSON. 20
